DESIGN FOR A WIRE RECORDER

Colin B. Dale, Oak Park, Ill., assignor to Webster-Chicago Corporation, Chicago, Ill., a corporation of Illinois

Application May 19, 1947, Serial No. 139,129

Term of patent 7 years

(Cl. D26—14)

To all whom it may concern:

Be it known that I, Colin B. Dale, a citizen of the United States, residing at Oak Park, in the county of Cook and State of Illinois, have invented a new, original, and ornamental Design for a Wire Recorder, of which the following is a specification, reference being had to the accompanying drawing, forming part thereof.

The figure is a perspective view looking toward the front and one side of a wire recorder, showing my new design.

I claim:

The ornamental design for a wire recorder, as shown.

COLIN B. DALE.
